ATTORNEY

UNITED STATES PATENT OFFICE

153,085

DESIGN FOR A TRUCK OR SIMILAR ARTICLE

John J. Powers, University City, Mo.

Application October 20, 1947, Serial No. 142,032

Term of patent 14 years

(Cl. D14—3)

To all whom it may concern:

Be it known that I, John J. Powers, a citizen of the United States, residing at University City, county of St. Louis, State of Missouri, have invented a new, original, and ornamental Design for a Truck or Similar Article, of which the following is a specification, reference being made to the accompanying drawing, forming a part thereof, in which Figure 1 is a side elevational view of a truck or similar article, embodying my new design showing the door thereof opened to show the interior design of the passenger compartment thereof; Figure 2 is a side elevational view thereof showing the opposite side to that shown in Figure 1; and Figure 3 is a perspective view thereof looking from the rear thereof.

The characteristic features of my design reside in the portions shown by means of full lines in the drawing.

I claim:

The ornamental design for a truck or similar article, substantially as shown and described.

JOHN J. POWERS.
